UNITED STATES PATENT OFFICE.

JOHN H. BASSLER, OF MYERSTOWN, PENNSYLVANIA.

APPARATUS FOR CONDENSING LIQUIDS.

SPECIFICATION forming part of Letters Patent No. 394,432, dated December 11, 1888.

Application filed February 24, 1888. Serial No. 265,119. (No model.)

To all whom it may concern:

Be it known that I, JOHN H. BASSLER, a citizen of the United States of America, residing at Myerstown, in the county of Lebanon 5 and State of Pennsylvania, have invented certain new and useful Improvements in Apparatus for Condensing Liquids, of which the following is a specification; reference being had therein to the accompanying drawing.

10 My invention relates to an apparatus for vaporizing and expelling the aqueous element contained in cane-juice, glucose, solutions of tannin, milk, &c.; and it consists in certain details of construction and combinations of 15 parts, which will first be described in connection with the accompanying drawing, and then pointed out in the claims.

In the accompanying drawing, which is a vertical section, partly in elevation, of my 20 apparatus, A represents a vertical evaporating-vessel, preferably cylindrical in form and having an outlet-flue, A', at its top, in which is placed a thermometer, t, the said vessel resting upon supports a, the bottom a' sloping downward and inward, and being open, as at a², so as to leave open communication 25 with the air-flue. The evaporating-vessel is also provided with a door, A², to afford access to the interior for cleaning it.

30 The evaporating-vessel is provided a short distance above its bottom with a non-heat-conducting hopper, B, constructed preferably of a sheet-metal casing, b, filled with mineral wool w. The diameter of the hopper is somewhat less than that of the lower part of the vessel A, by reason of which an annular space is left between the hopper and the walls of the vessel, in the upper portion of which is located a thermometer, t'. One end of a drain- 35 pipe, C, enters the hopper, and the other end enters a seal-cup, D, placed in the mouth of the receiving-can, E, the drain-pipe being provided with a stop-cock, F.

G represents an air-flue leading, preferably, 45 from a sub-earth duct, its upper end being in open communication with the interior bottom portion of vessel A. It is provided with a sliding-gate, g, working between cleats g' inside the flue, for governing the quantity of 50 air to be admitted to the evaporating-vessel. H represents an anemometer placed in the flue (shown in the drawing at a right angle to

its true position) for indicating the velocity, and consequently the quantity, of air admitted. The flue is also provided, opposite 55 the anemometer, with a glass window, g², through which the necessary observations of the anemometer may be made.

For the purpose of heating the air to be delivered to the evaporating-vessel, I place 60 any suitable number of Bunsen burners, I, in the air-flue a short distance below the bottom of the vessel, these burners being connected to a gas-pipe, I', leading from any suitable source of gas-supply. 65

J represents a liquid-holding box, (a fragment only of which is shown,) into which the liquid to be treated is placed.

K represents a steel pressure-cylinder provided at one end with a liquid-gage, k, and at 70 its opposite end with a draw-off cock, k'. There is also a man-hole in its top covered by a lid, k², for the purpose of access to the interior of the cylinder for cleaning it.

L represents an injector located between 75 the box J and cylinder K, with which are connected pipes l l', leading to the interior of the box and cylinder, respectively.

M represents a steam-pipe provided with a steam-pressure indicator, m, leading from any 80 suitable generator and entering the pressure-cylinder at its top, and N represents a branch steam-pipe leading from pipe N to the injector.

O represents a liquid-pipe, the lower end of 85 which enters and extends to near the bottom of the pressure-cylinder, and the upper end enters the evaporating-vessel, near its top, at a right angle, and is provided with a spraying device, P, so arranged as to spray the liquid in an outward and downward direction. The gas-pipe, liquid-pipe, and steam-pipes are each provided at a suitable place with a globe-valve, r.

The operation of my apparatus is very simple. The liquid to be treated is first placed in the box J. Steam is then let into the injector, which causes it to draw the liquid from the box and force it into the pressure-cylinder. When the gage k indicates the level of the liquid desired to be maintained in the cylinder, steam is let into the cylinder through pipe M. The pressure of the steam on the liquid forces the latter, mixed with steam, up through 90 95 100

the liquid-pipe O and into the vessel A, where it is sprayed in an outward and downward direction, the steam at once liberating itself from the liquid and passing off through the 5 exit-flue of the vessel, but meanwhile heating the upper portion of the vessel to a certain extent. It will be understood, however, that previous to this part of the operation the gas has been turned on to the burners and 10 the temperature of the air in air-flue G raised to the proper degree. Then as the descending films of liquid pass through a continuously-ascending current of hot air the desired per cent. of the aqueous element will, 15 sooner or later, be effectually evaporated and driven off, when the condensed liquid will flow from the hopper through the drain-pipe into the seal-cup, from which it will overflow into the can. As the seal-cup is never empty 20 during the time the apparatus is in operation, the liquid therein will prevent the admission of cold air through the drain-pipe into the evaporating-vessel.

It will be apparent that the purpose of the 25 anemometer is to indicate the volume of air entering the evaporating-vessel, while the thermometers are to show the temperatures at which the air enters and leaves that vessel, from the difference in which the operator can 30 readily calculate the velocity of the current of hot air, so as to prevent it from becoming so strong as to carry a portion of the liquid out with the vapor.

In another application for Letters Patent, 35 filed by me of even date herewith, I have shown and described certain portions of the apparatus embraced in the present applica-

tion, none of which portions, however, are claimed specifically herein.

Having thus described my invention, what I 40 claim as new, and desire to secure by Letters Patent, is—

1. The combination, with an evaporating-vessel having an outlet-flue at its top and an opening in its bottom, of an air-flue in communication with said opening, gas-burners in said flue, a pressure-cylinder, a steam-pipe entering the cylinder, and a fluid-pipe leading from the interior of the cylinder to the interior of the evaporating-vessel, near its 45 top, and provided with a spraying device so arranged as to spray the liquid downward, for the purposes set forth.

2. The combination, with an evaporating-vessel having an outlet-flue at its top and an opening in its bottom, of an air-flue in communication with said opening, gas-burners in said flue, a pressure-cylinder, a liquid-vessel, an injector in communication with said vessel and the cylinder, two steam-pipes, one 50 connected to the injector and the other entering the cylinder, and a liquid-pipe leading from the interior of the cylinder to the interior of the evaporating-vessel, near its top, and provided with a spraying device arranged 55 to spray the liquid downward, for the purpose set forth.

In testimony whereof I affix my signature in presence of two witnesses.

JOHN H. BASSLER.
